J. KAUPERT

LIFTING JACK

Filed Sept. 24, 1921

2 Sheets-Sheet 2

UNITED STATES PATENT OFFICE.

JOSEPH KAUPERT, OF CHICAGO, ILLINOIS.

LIFTING JACK.

Application filed September 24, 1921. Serial No. 502,934.

To all whom it may concern:

Be it known that I, JOSEPH KAUPERT, a citizen of the United States, and a resident of the city of Chicago, county of Cook, and

5 State of Illinois, have invented certain new and useful Improvements in Lifting Jacks, of which the following is a specification.

My invention relates to improvements in lifting jacks, and has for its object the provision of a simple and efficient construction of this character especially adapted for lifting the axles of automobiles and the like.

10 A further object of the invention is the provision of a simple and efficient device of this character by means of which a comparatively large elevating movement may be conveniently effected.

Other objects will appear hereinafter.

The invention consists in the combinations and arrangements of parts hereinafter described and claimed.

The invention will be best understood by reference to the accompanying drawings forming a part of this specification, and in

25 which,

Fig. 1 is a side view shown partly in section, illustrating a device embodying the invention and shown in position of use;

Fig. 2, an enlarged partial side view of

30 the device;

Fig. 3, a section taken substantially on line 3—3 of Fig. 2;

Fig. 4, a section taken substantially on line 4—4 of Fig. 2;

35 Fig. 5, a partial top plan view of the device;

Fig. 6, a detail view illustrating a folding joint employed in the lifting lever of the device; and

40 Fig. 7, a section taken substantially on line 7—7 of Fig. 5.

The preferred form of construction as illustrated in the drawings comprises a suitable base 8 having an upstanding hollow post 9 adjacent one end thereof. A lifting bar 10 is arranged to slide vertically in the hollow post 9 and is provided at its upper end with a rest 11 adapted to rest under the object to be lifted. The bar 10 is provided with a longitudinal slot 12 engaged by a bolt 13 extending transversely through the post 9 and whereby vertical movements of the lifting bar are permitted, but complete accidental removal of the bar prevented. The bar 10 is

55 also provided with a laterally extending pin

14, and a swinging catch 15 is provided on the post 9 to engage said pin to lock said lifting bar in its depressed position so as to facilitate transportation.

The lifting bar 10 is provided on one side with a plurality of ratchet teeth 16 co-operating with a lock rod 17 operating freely in inclined slots 18 formed in the sides of post 9 on opposite sides of the teeth 16 and whereby said locking rod will automatically engage with the teeth 16 to lock said lifting bar in its various positions of vertical adjustment. The bar 17 is provided with an operating finger 19 connected with a string or cable 20 by means of which said locking rod may be withdrawn from engagement with said teeth to permit of depression of the lifting bar 10.

A hollow fulcrum post 21 is pivoted at 22 between two lugs or ears 23 on the base 8 to permit of limited free lateral swinging of said post. At its bottom the post 21 is provided with a central notch 24 engaging a V-shaped abutment 25 on the base 8 and whereby the pivot 22 will be reinforced and rendered capable of standing heavy strains.

A fulcrum bar 26 is mounted for free vertical sliding in the post 21 and is provided with a longitudinal slot 27 engaged by a transverse bolt 28, as indicated, to permit free vertical movements but prevent actual displacement. A notch 29 is provided in the bottom of bar 26 to accommodate the pivot pin 22. The bar 26 is also provided with a laterally extending pin 30, and the post 21 with a co-operating latch 31 to lock said bar against removal from said post when desired.

A locking rod 32 is mounted in inclined slots 33 to co-operate with teeth 34 in the side of bar 26 to lock said bar in various positions of vertical adjustment. The locking rod 32 is connected, as indicated, with the other end of the cable 20 and whereby the locking rod 32 may be manually withdrawn from engagement with the teeth 34 when desired.

A lever 35 is pivotally connected at 36 with the lifting bar 10 and at 37 with the upper end of the fulcrum bar 26. The lever 35 is provided with a foldable extension 38 pivoted thereto at 39 and provided with a lateral extension 40 engaging under said lever, as indicated, whereby said lever may be folded when desired.

In use the rest 11 is placed under the object to be lifted, and the lever 35—38 manipulated to elevate said object, the fulcrum post 21 and bar 26 swinging laterally to permit 5 of free manipulation of said lever. If the lift thus obtained is not sufficient, the lever 26 is raised to elevate the fulcrum bar 26 in its post 21, whereupon the lever may be utilized to again raise the lifting bar 10. In 10 this manner the object to be lifted may be raised step by step to any desired height within the capacity thereof. When it is desired to lower the lifted object, the fulcrum post is first lowered by releasing the 15 locking rod 32, and then the lever 35 is held to temporarily support the object, and the lifting bar 10 lowered by releasing the locking rod 17. In this way the lifted object may be lowered step by step and thus 20 returned to original position.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope 30 of the appended claims.

Having described my invention, what I claim as new and desire to secure by Letters Patent, is:—

1. A device of the class described comprising a vertically movable lifting member; means for automatically locking said lifting member in various positions of vertical adjustment; a vertically movable fulcrum member; means for automatically locking 35 said fulcrum member in various positions of vertical adjustment; and a lever pivotally connected with both members, substantially as described.

2. A device of the class described comprising a vertically movable lifting member; means for automatically locking said lifting member in various positions of vertical adjustment; a vertically movable fulcrum member; means for automatically locking 40 said fulcrum member in various positions of vertical adjustment; manually operable means for independently releasing said automatic locking means; and a lever operatively connected with both of said members, substantially as described.

3. A device of the class described comprising a vertically movable lifting member; a vertically movable laterally swinging fulcrum member; and a lever operatively connected with both of said members, substantially as described.

4. A device of the class described comprising a vertically movable lifting member; means for automatically locking said 65 lifting member in various positions of ver-

tical adjustment; a vertical movable laterally swinging fulcrum member; means for automatically locking said fulcrum member in various positions of vertical adjustment; and a lever operatively connected with both 70 of said members, substantially as described.

5. A device of the class described comprising a vertically movable lifting member; means for automatically locking said lifting member in various positions of vertical adjustment; a vertically movable laterally swinging fulcrum member; means for automatically locking said fulcrum member in various positions of vertical adjustment; manually operable means for independently releasing said locking means; and a lever operatively connected with both 75 of said members, substantially as described.

6. A device of the class described comprising a base; an upstanding hollow post on said base; a lifting bar vertically slideable in said post; a plurality of ratchet teeth arranged along one side of said lifting bar; inclined slots in the sides of said post adjacent said teeth; a locking rod arranged in said slots and adapted to automatically engage said teeth; manually operable means for withdrawing said locking rod from said teeth; a lever pivotally connected with said lifting rod; a fulcrum bar 80 pivotally connected with said lever and depending therefrom; a hollow fulcrum post, receiving said bar for free vertical adjustment 85 therein, said fulcrum post being pivotally mounted on said base; a substantially V-shaped abutment on said base contacting with the bottom of said fulcrum post adjacent said pivot; ratchet teeth on one side of said ful-

crum bar; inclined notches in said fulcrum post adjacent said teeth; a locking rod freely slideable in said notches and adapted to engage said teeth; manually operable means for releasing said last mentioned locking rod; and a foldable extension handle for said lever, substantially as described.

In testimony whereof I have signed my name to this specification in the presence of two subscribing witnesses.

JOSEPH KAUPERT.

Witnesses:

JOSHUA R. H. POTTS,
FREDA C. APPLETON.
